UNITED STATES PATENT OFFICE

JOHN DEAN, OF RACINE, WISCONSIN, ASSIGNOR TO JOHN OSTER MANUFACTURING COMPANY, OF RACINE, WISCONSIN, A CORPORATION OF WISCONSIN

HAIR CLIPPER

Application filed January 26, 1932. Serial No. 588,981.

This invention relates to hair clippers; and the objects and nature of the invention will be understood by those skilled in the art in light of the following explanation of the accompanying drawings that illustrate what I now believe to be the preferred mechanical expression or embodiment of my invention from among other forms, constructions and arrangements within the spirit and scope of the invention.

A particular object of the invention is to reduce to the minimum side motion with resulting hair pull, in the operation of hand hair clippers, and to produce an improved hair clipper peculiarly adapted for home use by those not skilled in hand hair clipper operation.

A further object of the invention is to provide a hand hair clipper of the reciprocatory cutter blade type capable of being held and advanced by either the right or the left hand while actuated by the thumb or finger of such hand through a straight line operating pull approximately perpendicular and centrally arranged with respect to the front operating edge of the cutter blade, to maintain steadiness of the clipper head against side or lateral motion thereof and hair pulling which results from such side motion.

A further object of the invention is to improve structural features, arrangements and combinations, with the end in view of producing a simple, durable, and highly advantageous hand hair clipper.

A further object of the invention is to adapt to a hand hair cutter, the principle of a fire arm which in use is pressed against the shoulder or hand and is discharged by a finger trigger so arranged as to avoid causing lateral or side motion of the barrel to maintain barrel steadiness, when the finger moves the trigger rearwardly; with the end in view of promoting steadiness of the hair clipper head against side motion when in action, by providing the hair clipper head with a rigid rearwardly extending handle formed to seat at its rear against the palm portion of the hand while the clipper head with its transversely arranged cutter is being pushed forward on and pressed against the skin, and a

finger trigger located between the hand and clipper head for reciprocation by a finger or thumb of the hand in a preferably straight line perpendicular to the transverse front line of the cutter and intersecting said front line approximately midway its length.

With the foregoing and other objects, in view, the invention consists in certain novel features of structure, organization and/or combination, as more fully and particularly described and specified hereinafter.

Referring to the accompanying drawings, forming part hereof:

Fig. 1 is a side elevation of a hair clipper embodying my invention.

Fig. 2 shows the same in top plan.

Fig. 3 is a vertical longitudinal section on the line 3—3, Fig. 2.

Fig. 4 is a detail detached view of the slide normally located in the hollow stem of the frame, the bell crank normally operatively coupled to the reciprocatory blade for reciprocating the same, and the operating connection between said slide and bell crank.

Fig. 5 is a detail detached view of the preferably one-piece frame that provides the tubular shank and the head cap.

In the particular construction illustrated as an example of my invention, a relatively wide long flat bottom cutter or comb plate 1, is provided having a straight front row of parallel forwardly projecting cutting teeth 1a, throughout the length of its front edge. A relatively short flat cutter plate 2, that is relatively narrow from front to rear rests and reciprocates endwise on the forward portion of the top face of comb plate 1, and the straight front edge of cutter plate 2, throughout its length, provides a straight row of parallel forwardly projecting cutting teeth 2a, over and complementary to the teeth 1a, to slide thereon and cooperate therewith in hair cutting, preferably in the usual manner.

The cutter blades are, in the example shown, held in operative assembly by a cap 3, and a so-called tension bolt or stud 4, to form what is usually termed the hair clipper head. The cap 3, is approximately of inverted cup shape or of hollow open-bottom dome form, at its bottom rear edge formed with a central

depending rounded bearing abutment 3a, that bears or fulcrums on the central portion of the top face of the rear end of the comb plate, and at its front edge forming a straight transverse depending bearing edge or flange 3b, and a central relatively elongated depending tenon 3c. The bearing edge fits in a top groove throughout the length of reciprocating cutter blade 2, to confine said blade to straight line reciprocation, and the tenon 3c, extends down through elongated longitudinal slot 2b, in said cutter 2, removably into a mortise in comb plate 1, to limit the range of reciprocation of blade 2, and to maintain the plates and cap properly centered and aligned.

The preferably headed bolt or stud 4, rises from the comb plate, preferably along the center longitudinal front to rear axis thereof. Bolt 4, is preferably normally operatively fixed to the comb plate at a point in advance of the rear end of said plate and to the rear of the top cutter plate 2, and extends upwardly therefrom loosely through a hollow bearing stud 3d, rigid with the cap and depending therein from the top wall thereof, and through the top wall of the cap, and above the dome is preferably provided with a finger operated nut, such as wing nut 5, screwed on the upwardly projecting screw threaded end of the bolt, and a spring washer 6, interposed between the top surface of the cap and the nut, to function in holding the cap and plates or blades assembled and in controlling the tension or pressure of the top blade on the lower blade, in the usual or any other suitable manner.

I have thus described a hair clipper head assembly that is more or less typical of hair clippers in general use, but I do not wish to limit my present invention to this exact assembly although well adapted to my invention, as my invention can depart from this assembly and is adapted to other reciprocating blade hair clipper head assemblies.

In the particular embodiment illustrated as an example of my invention, I show cutter blade actuating mechanism that embodies a bell crank operatively coupled to the reciprocating blade, but do not wish to so limit all features of my invention. In this example, said bell crank is made in one piece and includes a vertically elongated hollow bearing hub 7, centered and rotatable on the fixed hollow bearing stud 3d, and formed with a rigid forwardly extending crank or lever arm 7a, with a depending front end removably entering and having loose bearing in a vertical socket or aperture 2c, in reciprocating blade 2, to reciprocate said blade by oscillation of the bell crank on its bearing stud 3d. Said hub 7, of the bell crank is also formed with a rigid radial arm 7b, projecting laterally therefrom, at an angle to arm 7a, say at an angle of 90°, and this arm 7b, is formed

at its free end with a vertical bearing opening or eye for the attachment of means for oscillating the bell crank back and forth throughout its full range of movement.

The main or supporting frame of my hair clipper embodies a longitudinally elongated preferably straight rigid shank 9, that extends upwardly and rearwardly from the hair clipper head at a suitable angle with respect to the flat bottom or comb plate or blade, for instance I find that an angle of approximately 45° is satisfactory, although my invention is not so limited. This shank is preferably located in the plane of the central longitudinal axis of the hair clipper, which plane preferably intersects at right angles the straight transverse row of teeth 1a, at a point midway the length thereof, and also preferably includes the axis of the bell crank and the tension bolt 4, although I do not wish to so limit all features of my invention. The rear portion of this shank 9, provides a transverse seat, cap or enlarged abutment 10 to take and afford firm steadyng and supporting bearing or seating against the inner or palm side of either hand that is operating the cutter. For instance, in the example illustrated, I show the rear end of the shank provided with a transverse normally fixed or rigid laterally enlarged cap, head or disk 10, of relatively large diameter presenting a concaved rear face of large area. The annular front face of this rigid cap, is preferably substantially concaved to afford a finger hold or to enable the little or other finger to grasp and hold the cap against the inner side of the hand, if so desired.

In the example illustrated, said main supporting frame is a single rigid unit, preferably, a strong rigid one-piece unit that includes or is composed of the shank 9, and the cap 3, of the hair clipper head.

The cap 3, forms one end of said frame forming an enlarged front end extension of the shank 9. The shank extends upwardly and rearwardly from the upper rear end of the cap and merges into the rear of the cap and provides the depending rear wall of the cap. The shank is longitudinally tubular or hollow and its bore at its front end opens into the upper rear of the chamber enclosed by the dome-like cap. The outer end of the bore of the tubular shank is closed by the enlarged transverse cap 10, which in the example shown has a rigid screw threaded stud 10a, that screws into the internally threaded rear end of the shank.

Any suitable actuating means is provided for actuating or reciprocating the transverse front hair cutting mechanism, and this actuating means includes a finger trigger 12, accessible at the exterior of the shank 9, movable longitudinally thereof and located between the enlarged end head 10, and the cap 3, of the hair clipper head. This trigger

12, is, in the example shown, in the form of a horn having its outer free end directed forwardly or of hook shape projecting radially from the shank and open at its front side, its 5 side facing the hair clipper head, and closed at its rear side that faces the head 10, of the shank. This trigger is thus formed so that a finger (and by finger I include thumb) of the hand against which shank head 10 is 10 held, can grasp or partially wrap around the hook and hold the shank rearwardly with its head 10, firmly seated against the palm portion of the hand, even while such finger in rapid succession pulls the trigger rearwardly 15 and then releases the same for its forward return stroke, to rapidly reciprocate the upper cutter blade. In other words, the trigger performs the double function of causing upper cutter blade reciprocation, 20 and while doing so cooperates with the finger caught around the trigger and alternating pulling back on and permitting forward movement of the trigger, in holding the shank steady and firmly against the palm of 25 the hand and thus constitutes an important element of the handle by which the hand holds and maintains the hair cutter while pressing the same against the skin and pushing the same forward.

30 In the example illustrated, the finger trigger is arranged longitudinally and exteriorly of the top or upper side of the shank 9, with its base approximately fitting the exterior surface thereof and the hook upstanding therefrom, and the trigger movable longitudinally of the shank, on its short back and return strokes, the full trigger stroke being usually not more than approximately one quarter of an inch or less.

40 Any suitable preferably spring-pressed movement transmitting and cutter blade reciprocating mechanism, operatively connects the trigger with said blade. For instance, I show a spring-pressed reciprocatory slide-block 14, longitudinally guided by and slidably arranged within the bore of the hollow shank 9, with its inner end operatively coupled to the eye of the bell crank arm 7b, by a stiff push and pull link connection 15, at 45 its front end bent approximately at right angles to enter and take bearing in said eye and at its rear end having a laterally bent end entering and taking bearing in eye 14a, in the front end of the block 14. This push and 50 pull link 15, extends longitudinally of the bore of the hollow shank 9, into the chamber within cap 3, wherein the bell crank is located, with ample room to move laterally as the slide block 14, reciprocates and the bell 55 crank arm swings laterally to rapidly oscillate the bell crank and reciprocate the cutter blade back and forth on its short cutting 60 strokes.

The slide block 14, is under constant urge 65 to remain in and return to its limit of for-

ward movement toward the hair clipper cutter head under the expansive power of a coiled expansion spring 16, longitudinally located in the bore of the shank 9, and compressed between the outer end of slide block 70 14, and the screwed threaded stud 10a, of the outer end cap of the shank.

The base of the finger trigger is preferably mounted on and carried by this slide plug, 75 for instance, through the medium of a radial pin 17, secured to both the block and the finger trigger base, and extending radially through a longitudinal slot 18, in the upper side of shank 9. If so desired, this slot can be short to define the desired possible stroke of the finger trigger, although my invention is not so limited. Also, the slide block is preferably so arranged and of such length as to always close said slot at its inner side 80 to prevent entrance of dirt or the like to the interior of shank 9. Also, if so desired, the radial 17, can constitute an axis on which the finger trigger can swing laterally to more comfortably accommodate the finger. Also, if so desired, the pin 17, can be screw threaded 85 into either the block or trigger base to permit separation of parts.

The hair clipper of my invention is by reason of its purposely peculiar formation and structure, adapted and intended for easy and convenient holding and operation by either the right or left hand, attaining maximum steadiness of the advancing cutter head with substantial elimination of objectionable lateral or side motion, when operated by either hand of even a person not skilled in the use of hair clippers. This hair clipper can be grasped, operated, pressed to the skin, and thus advanced in successfully performing its hair cutting functions, by various methods of hand and finger grips, although I prefer to grasp and operate the same by fitting the large area convexed surface of cap 10, of the handle or shank 9, against the inner side or palm of the hand, say against the ball of the thumb, with the shank extending forwardly between for instance, the middle and ring fingers and the middle finger in front of and fitting or grasping the finger trigger, and exerting rearward pressure thereon to hold the cap 10, firmly seated against the hand palm. The clipper can thus be held pressed against the skin and advanced thereon by the forward pressure of the hand on the cap 10, and can be guided and controlled by the fingers on the stem, all while the finger fitting the trigger rapidly increases and then diminishes the rearward pressure on the trigger to cause the desired short rapid reciprocation thereof 110 without causing lateral or side waving or play of the cutter head.

Also, the clipper can be grasped by placing the cap 10, against the palm of the hand adjacent the base of the little finger, for 115 120 125 130

instance, with the shank extending forward-
ly between the little and ring fingers, with
the little finger also if so desired, the ring
finger, curled back to fit in the front dished
5 or concaved side of cap 10, to hold the cap
against the palm, while the thumb, or possi-
bly a finger, fits the front side of the finger
trigger to constantly press said cap back
against the palm, even while the thumb by
10 rapidly alternating increased and diminish-
ing rearward pressures causes short rapid
reciprocation of the trigger and consequent
rapid reciprocation of the cutter blade.

As hereinbefore explained, steadiness of
15 the cutter head during the hair clipping op-
eration and consequent avoidance of objec-
tionable side motion, is attained because of
the location of the finger trigger (whatever
form of trigger may be employed) and the
20 direction of rearward pull thereon, along
the front to rear approximate longitudinal
central axis of the hair clipper, and between
the abutment of the supporting frame against
the hand and the approximate center of the
25 front edge of the cutters, said front edge be-
ing transverse and approximately perpendi-
cular to said longitudinal axis.

The pull on the trigger is directly rear-
wardly longitudinally of the shank or han-
30 dle 9 and against the palm of the hand,
while the rigid supporting frame composed
of handle 9, and cap 10, is rigid with the
hair clipper head, in fact forms part there-
of, with the handle extending rearwardly
35 from said head in the plane of the longi-
tudinal axis of the hair clipper that inter-
sects the transverse front edge of the comb
plate at approximate right angles midway
the length thereof. However, regardless of
40 the particular forms of trigger employed, or
of handle 9, or of the supporting frame of
which, in this example, it forms a part, this
frame is so formed and arranged and the
finger trigger is so arranged and supported
45 thereby, that the pull of the finger on said
trigger will be resisted by the palm or other
portion of the hand, without transmitting
such lateral or side stresses or strains on
the hair clipper head or supporting frame,
50 that will cause lateral or side waving or
motion of the cutting head during the hair
cutting operation. The steadiness of the cut-
ter head while in operation, is promoted by
the direct rearward pull on the trigger
55 against the tension of the spring 16, which
preferably is constantly exerting forward
pressure on the trigger even when the trig-
ger is at its limit of forward movement,
and hence the finger can always exert rear-
ward pressure on the trigger to hold and
60 maintain the cap 10, against the palm of
the hand, and thus the hair clipper is held
and grasped in position in the hand by the
65 rearward pressure of a digit of the hand that

holds said cap pressed against the palm of
the hand.

While I prefer to employ a trigger of the
approximate form shown, yet my invention
is not so limited, as the finger engaged mov-
able element for actuating the cutter blade,
70 can be of various forms and constructions,
and various movement transmitting means
can operatively couple the cutter blade to
such element, and hence, I herein employ the
75 term "trigger" in a broad generic sense or
meaning. Furthermore, I do not wish to
limit my invention to any particular form
of cap 10, or other abutment to firmly or
otherwise seat against the hand, nor do I
80 wish to limit all features of my invention to
approximately the form of the main or sup-
porting frame shown or to the form and
construction of cutter head shown.

Furthermore, certain generic features of
my invention are not limited to a hair clip-
per wherein the hair clipper cap 3, forms an
integral or rigid part of the supporting frame
such as handle or shank 9. In certain hair
clipper types embodying generic features
90 of my invention the cap 3, controlled by its
tension bolt can be a separate piece from the
rigid shank 9, or its equivalent.

What I claim is:—

1. A hand hair clipper having a front
head provided with transverse front recipro-
cating hair clipping means, said head hav-
ing a rigid approximately central longitudi-
nal rearwardly extending shank at its rear
100 end adapted to abut and seat against the palm
portion of the hand for pressing the head
against the skin and longitudinally advanc-
ing the same during the hair clipping op-
eration, and means for actuating said hair clip-
ping means including a spring-pressed trig-
105 ger movable longitudinally of said shank and
adapted to receive a digit of said hand to
press the shank against the palm portion
thereof by rearward pull on said trigger.

2. A hand hair clipper having relatively-
reciprocating cooperating cutting blades
providing a row of forwardly projecting
front cutting teeth, said row being arranged
transversely with respect to the front to rear
longitudinal axis of said clipper, said clip-
per embodying an upwardly and rearwardly
projecting longitudinal supporting frame
provided with a rear end enlarged head to
115 fit and abut the palm portion of the hand,
and mechanism for producing said relative
blade reciprocation, said mechanism includ-
ing an operating trigger carried by said
frame and exposed at the exterior thereof in
advance of said enlarged head to receive a
digit of said hand to cause back and forth
120 reciprocation of said trigger while holding
said frame rearwardly with its head pressed
back against the palm of said hand.

3. A hair clipper including hair clipping
means having a front cutting blade recipro-

catory transversely with respect to the front to rear longitudinal axis of the clipper; a rigid longitudinal supporting frame providing a rear abutment to seat back against the 5 palm portion of the hand pressing said clipper against the skin and pushing the same forward thereon; and mechanism for reciprocating said blade, said mechanism including an operating trigger to be pulled rearwardly by a digit of a hand to hold said rear abutment back against the palm of said hand while said digit actuates the trigger to operate said cutting blade.

4. A hair clipper having transversely arranged front hair clipping means, said clipper including a rearwardly extended handle to abut the palm portion of the operating hand when it is pressing the clipper to the skin and advancing the same thereon during 20 the hair clipping operation; and a trigger operatively coupled to said clipping means to actuate the same, said trigger being movable forwardly and rearwardly in a plane approximately perpendicularly and centrally 25 intersecting said front transverse cutting means, said trigger being arranged in advance of the palm portion of the hand operating the clipper to receive a digit of said hand for exerting backward pull on the trigger for holding said handle pressed back against the palm of the hand and for moving the trigger.

5. A hair clipper having a rigid longitudinally elongated supporting frame projecting upwardly and rearwardly and at its 35 rear formed with an abutment to seat rearwardly against the hand, said clipper having transversely arranged front hair clipping means; and mechanism for operating said 40 means, said mechanism including a finger trigger carried by said frame and movable backwardly toward said abutment and forwardly toward said clipping means, and spring means constantly acting on said trigger to force the same forwardly.

6. A hair clipper including transversely arranged front hair clipping means including a reciprocating blade; a rearwardly projecting supporting frame providing a rear 50 abutment to fit the operating hand and by which said hand advances the clipper; and means for reciprocating said blade including a spring device and a finger actuated operating trigger arranged exteriorly of said frame 55 in advance of said abutment in position to be pulled back by a finger of said operating hand to press said abutment back against said hand while also actuating said trigger, said trigger having a straight line back and forth movement approximately alined with the front to 60 rear longitudinal axis of the clipper.

7. A hair clipper including cutting blades with transversely arranged front rows of cutting teeth, at least one of said blades being reciprocatory; a main frame unit in

cluding a cap and a hollow rearwardly extending stem as rigid parts thereof; means for holding the cap and blades in operative assembly; and means for operating said reciprocating blade including crank means mounted in said cap and operatively coupled to said blade to reciprocate the same, a slide longitudinally reciprocating in said stem and operatively coupled to said crank means to oscillate the same back and forth, a finger trigger arranged at the exterior of said stem and movable longitudinally thereof in a straight line and coupled to said slide; and spring means constantly acting on said trigger to yieldingly hold the same in and return the same to its limit of movement in one direction.

8. A hand hair clipper of the hand-actuated cutter type having a single rigid rearwardly projecting shank or handle arranged in the plane of the central front to rear longitudinal axis of the clipper and provided with a finger trigger movable longitudinally thereof and connected to actuate said cutter, whereby said clipper is adapted to hair clipping operation under the guidance and actuation of either the right or left hand.

9. A hand hair clipper of the hand-actuated cutter type having a single rigid rearwardly projecting shank or handle arranged in the plane of the central front to rear longitudinal axis of the clipper and provided with a finger trigger movable longitudinally thereof and connected to actuate said cutter, whereby said clipper is adapted to hair clipping operation under the guidance and actuation of either the right or left hand, said trigger upstanding from an intermediate portion of the length of said handle in position for rearward pressure by a finger or thumb of either hand against the palm portion of which said handle is held.

10. A hand hair clipper of hand-actuated cutter type, provided with a finger trigger having straight line movement in the plane of the front to rear longitudinal axis of said clipper, and operative cutter actuating connection between said trigger and the hair clipper cutter.

11. A hand hair clipper of the hand-actuated cutter type, provided with a rear abutment to fit the palm portion of either the right or left hand, and a forwardly-spring-pressed finger actuated movable element in advance of said abutment and operatively connected with the hair clipper cutter to actuate the same, by backward pull of a finger or thumb toward said abutment.

Signed at Racine, county of Racine, State of Wisconsin, this 16th day of January, 1932.

JOHN DEAN.
